FIG. 1.

Inventor

BYRON S. ROSENBLATT,

BY Robert Burns, Attorney

UNITED STATES PATENT OFFICE.

BYRON S. ROSENBLATT, OF CHICAGO, ILLINOIS.

DESIGN FOR A NUTCRACKER.

47,831.

Specification for Design. Patented Sept. 14, 1915.

Application filed June 25, 1915. Serial No. 36,393. Term of patent 7 years.

To all whom it may concern:

Be it known that I, BYRON S. ROSENBLATT, a citizen of the United States of America, and a resident of Chicago, in the county of Cook, State of Illinois, have invented a certain new, original, and ornamental Design for Nutcrackers, of which the following is a specification, reference being had to the accompanying drawing, forming a part thereof, and in which—

Figure 1, is a side view of my new design. Fig. 2, is a bottom view of the upper member. Fig. 3, is a top view of the lower member.

I claim:—

The ornamental design for a nut-cracker, as shown.

BYRON S. ROSENBLATT.
